MASSACHUSETTS.

CARBURETER.

No. 853,196.

Specification of Letters Patent.

Patented May 7, 1907.

Application filed September 17, 1906. Serial No. 334,015.

To all whom it may concern:

Be it known that we, ANDERS AKESON and VERNER G. ANDERSON, citizens of the United States, residing at the city and county of Worcester and State of Massachusetts, have invented certain new and useful Improvements in Carbureters, of which the following is a specification.

Our invention relates to carbureters, of the class that is buried in the ground, and is an apparatus arranged to receive from a proper source compressed air and to pass the same over a volatile hydrocarbon, such as naphtha or gasoline, for the purpose of mingling said air with the hydrocarbon vapor in order to produce an illuminating gas of great lighting power.

With this object in view, our invention consists of the novel construction and combination of parts, as hereinafter described and specifically set forth in the claims.

Similar reference numerals in the drawing and in the specification indicate similar parts of the apparatus.

25 The figure represents a central longitudinal sectional view of our improved carbureter.

1 designates a vertically arranged cylindrical tank, which is closed by a top plate 2 and a bottom plate 3. Centrally of the top 30 plate 2 of the tank is secured a depending guide 4 arranged to have a sliding fit in a tubular head 5, which has an integral flange 6. A circular gas-dome 7 is provided with a central opening to receive the lower end portion of the tubular head 5, and said dome is secured to the flange 6 of said head by rivets.

35 8. The outer portion of the dome or gas-holder 7 terminates with a downwardly and inwardly directed flange 9.

40 10 designates a collapsible carbureting bag, made of burlap or other suitable absorbent material and formed into a series of rings whose inner and outer edges are sewed together and constituting a succession of 45 accordion folds. Said bag 10 has its upper ring or layer of burlap secured by rivets 11 to the inclined flange 9 of the gas-dome 7.

45 A hydrocarbon supply pipe 12 leads to a valve-casing 13, secured to a housing 14, 50 which in turn is secured to the side of the tank 1, and said housing has its chamber in open communication with the chamber of said tank. In the casing 13 is formed a valve-seat to receive a conical valve 15 hav-

ing an integral depending stem 16. The 55 upper end of said casing 13 is covered by a screw-cap 17, in which is secured the end of the hydrocarbon supply pipe 12, and between said cap 17 and said valve 15 is interposed an expansive coil spring 18 to force 60 against and tend to keep said valve closed upon its seat. The housing 14 has a bifurcated portion to receive a pivot center 19 of the rod connection 20 of a ball-float 21, and one end of the rod connection of said 65 float 21 is adapted to contact with the depending stem of the valve 15 in lifting the same from its seat, while the hydrocarbon liquid is admitted through the pipe 12, such liquid falling into the tank and fills the same, 70 to the level indicated by the dotted line 22. When the liquid has reached this level the float has risen to such a height as to permit of the spring 18 closing the valve 15, thereby preventing further ingress of the hydrocarbon liquid, while the level 22 is maintained.

75 Centrally of the bag 10 is an inverted U-shaped yoke comprising two vertical rods 23, having knobs 24 secured on their lower ends to rest upon the bottom plate 3 of the tank 1, 80 and the upper portion of said rods terminating with a central upwardly projecting screw-threaded stem 25, which is secured in the tubular head 5 of the gas-dome 7. This yoke acts as a support for the gas-dome and is of 85 such height as to permit the flange portion 9 of said dome being submerged in the hydrocarbon liquid, during the time that the hydrocarbon vapors are filling within said dome.

90 When the tank has been charged with the hydrocarbon liquid, to the normal level described, air is forced through the pipe 26, which leads up above the level of said liquid and thence passes through branch pipe connections 27 that discharge the air beneath the level of said liquid. As the vapor accumulates within the gas-dome, said dome rises, and as the bag 10 is carried up by said dome its accordion folds open. Thus, when 100 the dome has reached its upward position, indicated by dotted lines, the carbureted vapor within the dome passes through the bag and fills the upper portion of the tank, and the distended portion of said bag serves 105 to throw off the evaporation or absorbent vapors held in suspense, when the bag was entirely submerged in the liquid. As the up-

per portion of the bag rises above the level of the hydrocarbon liquid, an evaporation of said liquid takes place and its volatile elements pass off in vapor. From the tank the 5 gas eventually emerges through pipes 28, which extend from above the level of the liquid, to the point of consumption.

The extent of movement of the gas-dome 7 is limited by means of a disk-plate 29, which 10 is secured to the yoke-rods 23, said disk coming in contact with and closing the air-discharge openings of the pipes 27, to the position indicated by dotted lines. As the level 15 of the hydrocarbon liquid falls, the float 21 will fall with it, and will open the valve 15, which will remain open until the liquid has 20 been restored to its former normal level, this operation of alternately opening and closing the valve 15, being automatically performed 25 and serving to maintain the hydrocarbon liquid at substantially a constant level in the apparatus. A drainage or pump-out pipe 30 extends from near the bottom of the tank 1, to a point above the ground, the purpose of 35 this pipe being to provide for the withdrawal of any condensed moisture that may accumulate at the bottom of said tank.

What we claim and desire to secure by Letters-Patent, is—

30 1. In a carbureter, the combination of a vertical closed tank adapted to contain a hydrocarbon liquid; a guide centrally secured to the top of said tank; a tubular head to receive said guide; a gas-dome centrally secured 35 upon said head, and said dome having its outer portion terminating with a downwardly and inwardly directed flange; a carbureting bag of absorbent material formed into accordion folds whose upper layer is secured to 40 the flange of said dome; a yoke secured to said head to support said dome so that its flange may be submerged in said liquid; an air-inlet-pipe extending above the level of the liquid in said dome and beneath the 45 surface of said liquid; a disk secured upon said yoke to close the discharge end of said pipe beneath the level of said liquid; a gas-discharge-pipe extending from above the level of said liquid in the tank; an oil-feed-pipe, and 50 a governing valve constructed to maintain said liquid at substantially a constant level within said tank.

2. In a carbureter, the combination of a closed tank adapted to contain a hydrocarbon liquid; an inlet-pipe arranged to discharge air beneath the level of said liquid; a gas-dome above said pipe; a support carried by said dome; a disk secured to said support to close the air discharge from said pipe when

the dome has reached its highest limit of 60 travel; a collapsible carbureting bag of absorbent material surrounding said pipe and secured to said dome; a housing secured to said tank and having its chamber in open communication with the interior of the same; 65 a casing mounted on said housing; an oil-feed-pipe communicating with the chamber of said casing; a spring pressed valve within said casing; a float - connection pivotally mounted in said housing to open said valve, 70 and a gas-outlet-pipe extending from above the level of the liquid in said tank.

3. In a carbureter, the combination with a closed tank having an oil feed-pipe and a governing valve to maintain the oil at substantially 75 a constant level within said tank, of a gas-dome whose outer portion enters beneath the level of said liquid; a carbureting bag of absorbent material having its top secured to the outer portion of said dome; a 80 yoke within said bag, carried by said dome to support the latter above the level of said liquid; an inlet-pipe below said dome to discharge air beneath the level of said liquid; a disk carried by said yoke to close off the discharge of air from said pipe and at the same time prevent further upward movement of 85 said dome, and a gas discharge-pipe extending from above the oil level in said tank.

4. In a carbureter, the combination of a 90 closed tank adapted to contain a hydrocarbon liquid; an automatically operated valve constructed to govern the inlet of said liquid to a normal level within said tank; a gas-dome having its open end submerged in said 95 liquid; a tubular head centrally secured upon said dome; a guide secured to the top of said tank and having a sliding fit in said head; a support carried by said dome to prevent further downward movement of the dome in 100 said liquid; a carbureting bag of absorbent material surrounding said support, formed into accordion folds and having its top secured to the open end portion of said dome; a pipe to discharge air beneath the level of 105 said liquid within said bag; a disk secured upon said support to close off the air supply from said pipe when said dome has reached its upward limit of movement, and a gas outlet pipe from above the level of the liquid 110 within said tank.

In testimony whereof we affix our signatures in presence of two witnesses.
